[57] CLAIM

The ornamental design for a shoe chain, as shown and described.

DESCRIPTION

FIG. 1 is a front elevational view of the shoe chain showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a side elevational view thereof in use condition,
the broken line showing is for illustrative purposes
only and forms no part of the claimed design.

*FIG. 1**FIG. 2*FIG. 3

FIG. 4

*FIG. 5**FIG. 6*FIG. 7
